CAMERA SUPPORT

David Robinson, 4750 N. Clarendon, Chicago, Ill.

Filed May 13, 1963, Ser. No. 74,868

Term of patent 14 years

(Cl. D61—1)

FIG. 3 is a front elevational view thereof;

I claim:

The ornamental design for a camera support, as shown and described.
